UNITED STATES PATENT OFFICE

2,447,275

SHINGLES AND CLIPS THEREFOR

James G. Price, Coalgrove, Ohio

Application August 13, 1946, Serial No. 690,133

5 Claims. (Cl. 108—8)

1

This invention relates to shingles and shingle clips and, more particularly to a shingle locked into place by co-operating surfaces on the shingle and clips therefor.

The primary object of the invention is to provide a shingle which may be precast of cementitious or other known building composition which, when set, forms a relatively hard, rigid body, and a clip for locking it in place, the shingle having substantially smooth and continuous edges and being devoid of nail and screw holes, notches, or other apertures through its body or edge. With this arrangement, it is intended to provide a shingle which, while conventional in outward appearance, may be laid in different patterns with various spacing without necessitating close fitting, at least laterally, with the fastening clips, and without danger of cracking by securement of the clips.

More particularly, it is intended to provide a shingle, preferably rectangular in plan, and having a body tapering in thickness from the bottom to the top, the bottom of the shingle being undercut so as to form a flange for overlying the tops of the lower adjacent shingles and so as to form a hidden recess for accommodating the fastening clips. Furthermore, the upper longitudinal edge of each shingle is to be formed with a bevel extending upwardly from the face to the base, whereas the hidden longitudinal edge at the top of the undercut is to have a bevel extending upwardly from the base to the flange. Sheet metal clips having flat bases with screw or nail holes for securement to sheathing, and wing-like projections angling above and below the base for engaging the bevels are to be provided for locking the shingles to the sheathing.

These and other objects will be apparent in the following specification and drawings, in which:

Fig. 1 is a plan view showing several shingles in place, broken away to show the hidden elements and a locking clip;

Fig. 2 is a vertical cross section along the lines 2—2 of Fig. 1;

Fig. 3 is a plan view of the locking clip;

Fig. 4 is a cross-section of the clip shown in Fig. 3 taken along the lines 4—4;

Fig. 5 is a plan view of a wooden locking strip usable with the shingles illustrated in Figs. 1 and 2; and

Fig. 6 is a cross-section taken along the lines 6—6 of Fig. 5.

Referring now to the drawings, in which like reference numerals denote similar elements, the

2

shingles 2 constructed of cast or molded conventional material such as concrete, any one of the well known cementitious compositions, asbestos, or the like relatively rigid-setting material are generally rectangular in plan and somewhat tapered in thickness from bottom to top, as seen in Fig. 2. The exposed longitudinal edge 4 at the bottom of each shingle may be somewhat rounded and the vertical side edges 6, while illustrated as straight, may be roughened or otherwise configurated for variety. Each longitudinal top edge 8, however, is beveled so as to present an inclined surface 9 running continuously between the vertical side edges 6 and extending upwardly and inwardly from the shingle face 10 to the base 11.

The lower inside portion of each shingle is cut away to form a hidden recess 12 and to leave a flange 13 for overhanging the top edges 8 of the adjacent shingles below, the shingle being cast to provide a further undercut so as to form the hidden longitudinal edge 14 as a bevel extending between side edges 6 with its inclined surface 15 extending upwardly from base 11 to flange 13.

Shingles 2 are locked in place by clips 16 preferably formed of sheet metal which may be stamped or bent of a flat stock to provide a flat base 18 having screw or nail holes 20, and wings 22 upwardly inclined from the lower and upper longitudinal edges of the base for face engagement with inclined surfaces 9 and 15 on the upper and lower edges 8 and 14 of the vertically adjacent shingles 2. While the shingles 2 and clips 16 may be used on conventional sheathing 26 placed over studding 28 as shown, they also may be supported on slats or battens suitably spaced on a building framework.

From the foregoing disclosure it is apparent that a wall or roof may be shingled by screwing or nailing on the side or roof of a building a series of longitudinally spaced clips 16, laying on a course of shingles 2 with their hidden longitudinal edges 14 slid beneath the uppermost of wings 22, then fastening down another series of clips 16 with their lowermost wings 22 engaged against the beveled top edges 8 of the layed shingles, and then repeating the procedure with the subsequent upper courses. It should be noted particularly that the longitudinal spacing of clips 16 is not critical so long as each shingle receives adequate vertical support as by two clips, and that the shingles need not be closely fitted to the clips, thereby rendering variations in shingle width harmless. Where greater ver-

55

tical spread of the shingles is desired, two vertically offset clips may be used side-by-side to increase the effective distance between their upper and lower wings 22.

A modification of the invention having some of the advantages of clip 16 is illustrated in Figs. 5 and 6 which show an elongated wood strip 30 frusto-conical in cross section and having a flat base 32, beveled longitudinal edge 34 and screw holes 36 to facilitate fastening to sheathing. Strips 30 may be of various lengths and may lie continuously along the shingle joints or may be spaced at intervals. Where shorter strips are used, it is preferred that they be long and frequent enough to bridge beneath the butt-joints between the laterally adjacent shingles.

The invention, although disclosed in detail, is not limited to the exact showing but is intended to cover all equivalents and modifications within the scope of the following claims:

I claim:

1. In combination a plurality of similar shingles, each tapered in thickness from bottom to top and having a longitudinal recess extending from side-to-side in the lower portion of the base face thereof, a downwardly extending flange overhanging said recess, the lower portion of said flange being adapted to overlie the upper edge of an adjacent similar shingle therebelow, the upper edge of said recess being defined by a beveled surface inclined upwardly from said base face to said flange, the upper edge of said shingle being beveled to present a surface extending from side-to-side and inclined upwardly from the lower face of said shingle to the upper face thereof, and fasteners for said shingles comprising a plurality of members each having a base portion adapted for securement to a support and other portions presenting inclined surfaces angling upwardly and outwardly from said base portion on the upper and lower sides thereof for face engagement, respectively, over the upper edge of one shingle and the surface defining the upper edge of the recess on the next adjacent shingle thereabove.

2. The combination claimed in claim 1, said members comprising sheet metal clips, the base portions thereof being flat and having holes therethrough for screws or nails, said other portions comprising pairs of wing-like elements respectively integral with said base portions.

3. The combination claimed in claim 1, said members comprising elongated strips of wood or the like material substantially frusto-conical in transverse cross section.

4. In combination, a support, a shingle having a base surface resting on said support, a face surface, and upper and lower edge portions, said upper edge portion comprising a beveled surface inclined towards the lower edge portion from said base surface to said face surface, said lower edge portion comprising a downwardly extending flange forming a continuation of said face surface and overhanging a recess, the upper edge of said recess comprising a beveled surface inclined toward said upper edge portion from said base surface to said flange, and a fastener having a base secured to said support and having inclined walls extending upwardly and outwardly from said base portion in face engagement with the adjacent beveled surfaces on superposed shingles.

5. The combination claimed in claim 4 said fastener comprising a sheet metal clip, said base portion being flat and having screw holes therethrough, said walls being formed by wings integral with an angling upwardly from said base portion.

JAMES G. PRICE.
